UNITED STATES PATENT OFFICE.

ALFRED F. SASS, OF NEW YORK, N. Y.

DESIGN FOR A FINGER-RING, CANE-RING, UMBRELLA-RING, BAR-PIN, OR SIMILAR ARTICLE.

52,676.

Specification for Design.

Patented Nov. 12, 1918.

Application filed August 13, 1918. Serial No. 249,740. Term of patent 3½ years.

To all whom it may concern:

Be it known that I, ALFRED F. SASS, a citizen of the United States, and a resident of New York city, in the borough of Bronx and State of New York, have invented a new, original, and ornamental Design for Finger-Rings, Cane-Rings, Umbrella-Rings, Bar-Pins, or Similar Articles, of which the following is a specification, reference being had to the accompanying drawing, forming part thereof.

The figure is a plan view of a finger ring, with the shank unbent, showing my new design.

I claim:

The ornamental design for a finger ring, cane ring, umbrella ring, bar pin, or similar article substantially as shown.

ALFRED F. SASS.
